CLAIM

The ornamental design for a hinged releasable buckle, as substantially shown and described.

DESCRIPTION

FIG. 1 is a perspective view of a hinged releasable buckle showing my new design, taken from the top and front thereof, the dotted lines depicting environmental subject matter only and forming no part of the claimed design;

FIG. 2 is a further perspective view of my new design taken from the top and front thereof with the right side portion rotated downwardly;

FIG. 3 is a further perspective view of my new design taken from the top and front thereof with the right side portion rotated upwardly;

FIG. 4 is a bottom plan view thereof;

FIG. 5 is a top plan view thereof;

FIG. 6 is a front side elevational view thereof; and,

FIG. 7 is a rear side elevational view thereof.
